UNITED STATES PATENT OFFICE

NANCY E. VEATCH, OF GALES CREEK, OREGON.

HAT OR BONNET HOLDER.

SPECIFICATION forming part of Letters Patent No. 393,595, dated November 27, 1888.

Application filed September 10, 1887. Serial No. 249,369. (No model.)

To all whom it may concern:

Be it known that I, NANCY ELLEN VEATCH, of Gales Creek, in the county of Washington and State of Oregon, have invented a new and Improved Hat or Bonnet Holder, of which the following is a full, clear, and exact description.

My invention relates to a novel device to be attached to ladies' and children's hats or bonnets, for holding them upon the head; and the invention consists of a coil of fine wire combined with fastening devices at its ends for securing the coil to a hat or bonnet, the coil being of suitable length to pass under the hair of the wearer, and of sufficient elasticity to close snugly upon the hair and head.

The invention also consists in providing the coil with a safety-cord to prevent the hair from passing between the coils, and thus getting fastened therein, and to prevent the wire from being stretched too far.

Reference is to be had to the accompanying drawings, forming a part of this specification, in which similar letters of reference indicate corresponding parts in all the figures.

Figure 1 shows my invention applied to a hat. Fig. 2 is an enlarged view of the device removed from the hat. Fig. 3 is an enlarged sectional elevation of a portion of the device, and Fig. 4 is an edge view of one of the fastening-plates. Fig. 5 is an enlarged sectional view of the plate C, wire B, shank b', and screw f'.

A represents a coil of fine elastic wire of sufficient length to reach from side to side of a hat or bonnet and to pass under the back hair of the wearer. Each end of the elastic coil is provided with a U-shaped wire, B, the ends of which are turned outward, as shown at a a. The wires B are pivoted in the fastening devices or plates C, which are adapted to be stitched to the hat or

bonnet through small orifices c c. These plates 40 are each provided with a loop, d, in the sides of which are formed the orifices e e, in which the ends a of the wires B fit, as shown clearly in Fig. 3. By springing the members of the wires B inward they may be detached from the loops 45 d for convenience in fastening and for removing the coil from one hat or bonnet and attaching it to another.

The U-shaped wires B are adapted to be screwed into the ends of the coil by threaded 50 shanks b', (shown in Fig. 3,) and within the coil is placed the cord f, which, passing through holes in the points f', is then made fast at its ends, the purpose of the cord being to prevent the hair from passing through between the 55 coils, and also to retain the wire and prevent it from being injured by stretching the coil too far. I may use cord, braid, tape, thread, or ribbon to place within the coil.

Having thus fully described my invention, I 60 claim as new and desire to secure by Letters Patent—

1. The fastening devices or plates C, provided with the loops d, having orifices e, in combination with the fastening-wire B and coiled elastic 65 spring A, the ends of the wires B being turned outward, as and for the purposes set forth.

2. The coiled elastic wire A, provided with the screws f', in combination with the cord f, attached to the screws, for preventing the hair 70 from passing between the coils, said screws being made fast to the threaded shanks b' of the U-shaped wires B, substantially as shown and described.

NANCY E. VEATCH.
